UNITED STATES PATENT OFFICE.

FRANK SCOVILLE, OF OAKLAND, CALIFORNIA, ASSIGNOR OF ONE-HALF TO AVERY SCOVILLE, OF OAKLAND, CALIFORNIA.

LENS-GRINDING MACHINE.

1,003,816.

Specification of Letters Patent. Patented Sept. 19, 1911.

Application filed January 24, 1910. Serial No. 539,654.

To all whom it may concern:

Be it known that I, FRANK SCOVILLE, a citizen of the United States, residing at Oakland, in the county of Alameda and State of California, have invented new and useful Improvements in Lens-Grinding Machines, of which the following is a specification.

This invention relates to machines for grinding and polishing lenses, and particularly pertains to lens grinding machines which are adapted to grind cylinder, toric cylinder or other lenses having compound curvatures.

It is the object of this invention to produce a lens-grinding machine in which simple means are provided for moving the lens across the grinding tool, and having means whereby the lens and the grinding tool may both be revolved simultaneously in the same direction and in such manner that the axis of the lens, and the corresponding axis of the grinding tool will maintain a parallel relation to each other at all periods of the grinding operation.

A further object is to provide means whereby the lens may be lifted from the grinding tool so as to permit of the application of fresh grinding or polishing materials.

Another object is to provide a lens-carrying block which can be readily removed from the machine so that the operator may occasionally inspect the work.

The invention consists of the parts, and the construction and combination of parts as hereinafter more fully described and claimed, having reference to the accompanying drawings, in which—

Figure 1 is a vertical section of the invention on the line $\alpha-\alpha$ Fig. 2. Fig. 2 is a plan view. Fig. 3 is a detail in side elevation of the lens-holder. Fig. 4 is a front view of same. Fig. 5 is a diagram illustrating the relative position of the lens and the lens grinding tool. Fig. 6 is a front view of the machine, with a portion broken away. Fig. 7 is a diagram in plan, showing the parallel position of the corresponding axes of the lens and grinding tool, as the former travels across the face of the latter. Fig. 8 is a detail in vertical section of the adjustable eccentric.

In the drawings A represents the base or bed-plate of the machine, which may be con-

structed and mounted in any suitable manner. A standard 2 is formed on the bed-plate A, and is adapted to support a housing or carriage 3 which is swivelly mounted on the standard 2 and adapted to be oscillated or swung from side to side thereon as later described.

A drive-shaft 4 extends upward through the standard 2, the upper end terminating within the housing or carriage 3; this upper end being fitted with a pinion 5 which meshes with an idler-gear 6 suitably mounted within the housing. The drive-shaft 4 is also provided with a pinion 7, corresponding in size to the pinion 5. The pinion 7 is secured to the shaft beneath the bed-plate A and meshes with an idler-gear 8, a trifle smaller in size than the idler-gear 6 suitably mounted on the underside of the bed-plate, as shown in Fig. 1.

A spindle 10, carrying a grinding tool 11, is provided with a gear 12 which meshes with the idler 8. The spindle 10 extends through, and is supported upon a standard 13 on the bed-plate A, and is provided with a dust-cap 14 beneath the tool 11.

A lens-carrying spindle 15 is vertically mounted in the housing 3, and is adapted to be reciprocated up and down by means of a lever 16, fulcrumed at 17, and so constructed as to be connected to a foot-pedal at one end, and is provided with a handle 16' at the opposite end.

A gear 17 mounted on the spindle 15 meshes with the idler-gear 6 on the inside of the housing 3, and is of such length as to be in constant engagement with the gear 6, irrespective of the position assumed by the spindle 15 as it is moved up or down by the lever 16.

A yoke 18 is formed on the lower end of the spindle 15, in which a spider or cross-arm 19 is pivotally mounted. The outer free ends of the cross-arm are provided with upwardly and downwardly projecting flanges which carry a device for engaging and disengaging the lens-carrying disk or block 20.

Oppositely disposed lugs 21—21 are formed on the lens-carrying block 20, and are perforated at their upper ends with holes 22 which are adapted to register with corresponding holes in the downwardly projecting flanges on the cross-arm 19.

Mounted in the upwardly projecting

flanges on the cross-arm 19 is a pair of parallel disposed pins 23, which extend horizontally across the cross-arm, one end of each pin being provided with a button or head 24, and the opposite end being bent downward and inward so that the opposite end 25 will extend through the holes in the lower flanges and project into the holes 22 in the lugs 21 of the lens-holding block 20. Stiff springs 26 act upon the pins 23 to normally retain the ends 25 in engagement with the disk 20 as shown in Fig. 4. By pressing the buttons or heads 24 toward each other, and in opposition to the springs 26, the ends 25 will be withdrawn from the holes 22, and this permits of the ready removal of the lens-carrying block 20.

The housing 3, carrying the idler gear 6 and the lens-carrying spindle 15 is turned from side to side on the standard 2, by means of an adjustable eccentric 27 which is mounted on a vertical shaft 28, and is driven from the drive-shaft 4 through the pinion 7, idler 9 and a gear 29 on the lower end of the shaft 28, said pinion 7, meshing with the idler 9. The eccentric is connected to the housing 3 by means of a link connection, an arm 30 on the housing 3 being pivoted at 31 to the eccentric arm 32.

In operation the lens to be ground is fastened to the under side of the lens-carrying block 20, with a suitable cement. Emery or other desired grinding or polishing material is then placed upon the grinding tool 11 in the usual manner. The grinding tool 11 and the lens-carrying block 20 are then caused to revolve in the same direction by driving the shaft 4 in any suitable manner. At the same time, the lens-carrying block 20, with its lens, is caused to travel back and forth over the grinding tool by means of the eccentric 27 and its connections, which swing the housing 3 on the standard 2. The lens is then brought in contact with the grinding tool, the weight of the gear 17 being sufficient to retain the lens upon the tool.

By lifting the lever 16 by the lever 16', the block 20 may be raised to its uppermost position so that when the lens is lifted from the grinding tool 11 into the position shown in Fig. 1, it permits of the application of fresh emery or other grinding material to the grinding tool 11 without necessitating the stopping of the machine.

The grinding action of this machine is accomplished in the essential manner necessary to the successful manufacture of lenses, which is to constantly maintain the axis of the lens, and the corresponding axis of the grinding tool in parallel relation, as illustrated in diagram in Fig. 7. It will be seen that by virtue of the idler-gears 6 and 8, through which motion is transmitted to the grinding tool and the lens-carrier, from the drive-shaft 4, the gears 12 and 17, and their

spindles will maintain the same relative position regardless of the position of the housing 3, the gears, 5, 7, 12, 17 being of the same diameter.

The idler-gear 6 in the housing 3 is slightly larger in diameter than the idler 8 and the gears 12 and 17 are of equal diameters thus disposing the shafts 10 and 15 slightly eccentric to each other. By this construction the lens on the lens carrying block 20 on the shaft 15 will be carried across the grinding tool 11 in such manner that the center of the lens will be slightly eccentric to the center of the tool as shown in Fig. 5, thus insuring a constant grinding action.

While I have shown spur-gears in the drawings, it is obvious that the same results can be accomplished through the medium of bevel gearing, spiral gearing, cranks, or their equivalents. It is also apparent that one, two, or more grinding spindles and lens-carrying spindles can be mounted around the pinions 5-7 and be driven through idler-gears, similar to 6-8, but I prefer to employ two, as illustrated in the drawings in Figs. 2 and 6, as by this arrangement a pair of lenses can be ground at one operation.

Having thus described my invention, what I claim and desire to secure by Letters Patent is—

1. In combination with a lens-grinding machine, means for removably engaging the lens-holder with the lens-carrying spindle, comprising a cross-arm pivotally mounted at its ends on said spindle, and oppositely acting spring-pressed means on said cross-arm for engaging a lens-carrying disk substantially as described.

2. In a lens-grinding machine having a rotatable grinding tool and a rotatable lens-holder mounted eccentric to the grinding tool, means for rotating the grinding tool and the lens-holder in the same direction, said means comprising a vertically disposed drive shaft, a pinion on the upper end of said drive shaft, an idler gear meshing with said pinion, a pinion on a lens-carrying spindle meshing with said idler gear, and a second pinion on said drive shaft meshing with an idler gear meshing with a pinion to rotate the grinding tool.

3. In a lens-grinding machine having a rotatable grinding tool and a rotatable lens-holder mounted eccentric to the grinding tool, means for rotating the grinding tool and the lens-holder in the same direction, said means comprising a vertically disposed drive shaft, pinions on the drive shaft meshing with idler gears, separate spindles carrying the grinding tool and the lens-carrier, and gears on said spindles meshing with the idler gears.

4. In a lens-grinding machine having a rotatable grinding tool and a rotatable lens-

holder mounted eccentric to the grinding tool, means for rotating the grinding tool and the lens-holder in the same direction, said means comprising a vertically disposed drive shaft, pinions on the drive shaft meshing with idler gears, separate spindles carrying the grinding tool and the lens-carrier, gears on said spindles meshing with the idler gears, and adjustable means for moving said lens-holder back and forth across the grinding tool.

5. In a lens-grinding machine, the combination of a bed plate, a tubular standard formed thereon, a housing pivotally mounted on the tubular standard, a vertical lens carrying spindle slidably mounted in the housing, a gear fixed on said spindle, and transmitting gears within the housing, means for operating said transmitting gears, and adjustable means for oscillating said housing on the standard.

6. In a lens-grinding machine, the combination of a bed plate, a tubular standard vertically disposed thereon, a housing pivotally mounted on the standard, adjustable means for oscillating said housing, a vertically disposed drive shaft extending through said standard terminating in said housing, a pinion on the upper end of said drive shaft, an idler gear mounted on the housing meshing with said gear, a lens-carrying spindle vertically mounted in the housing, and a gear fixed on said spindle in constant mesh with said idler gear and rotatable thereby.

7. In a lens-grinding machine, the combination of a bed plate, a tubular standard vertically disposed thereon, a housing pivotally mounted on the standard, adjustable means for oscillating said housing, a vertically disposed drive shaft extending through said standard terminating in said housing, a pinion on the upper end of said drive shaft, an idler gear mounted on the housing meshing with said gear, a lens-carrying spindle vertically mounted in the housing, a gear fixed on said spindle in constant mesh with said idler gear and rotatable thereby, means for reciprocating said spindle while being rotated, and while the gear thereon is in mesh with the idler, a pinion on the drive shaft below the bed plate, an idler gear mounted on the bed plate in mesh therewith, a vertically disposed spindle mounted in said bed plate, and a gear on said spindle in constant mesh with said idler and rotated thereby to revolve the spindle.

8. In a lens-grinding machine, the combination of a bed plate, a tubular standard vertically disposed thereon, a housing pivotally mounted on the standard, adjustable means for oscillating said housing, a vertically disposed drive shaft extending through said standard terminating in said housing, a pinion on the upper end of said drive

shaft, an idler gear mounted on the housing meshing with said gear, a lens-carrying spindle vertically mounted in the housing, a gear fixed on said spindle in constant mesh with said idler gear and rotatable thereby, means for reciprocating said spindle while being rotated and while the gear thereon is in mesh with the idler, a pinion on the drive shaft below the bed plate, an idler gear mounted on the bed plate in mesh therewith, a vertically disposed spindle mounted in said bed plate, and a gear on said spindle in constant mesh with said idler and rotated thereby to revolve the spindle, the gear on the lens-carrying spindle being of smaller diameter than the gear on the last named spindle and said spindles being disposed eccentric to each other.

9. In a lens-grinding machine, the combination of a bed plate, a tubular standard vertically disposed thereon, a housing pivotally mounted on the standard, a vertically disposed drive shaft extending through said standard terminating in said housing, a pinion on the upper end of said drive shaft, an idler gear mounted on the housing meshing with said pinion, a lens-carrying spindle vertically mounted in the housing, a gear fixed on said spindle in constant mesh with said idler gear and rotatable thereby, means for reciprocating said spindle while being rotated and while the gear thereon is in mesh with the idler, a pinion on the drive shaft below the bed plate, an idler gear mounted on the bed plate in mesh therewith, a vertically disposed spindle mounted in said bed plate, a gear on said spindle in constant mesh with said idler and rotated thereby to revolve the spindle, the gear on the lens-carrying spindle being of smaller diameter than the gear on the last named spindle and said spindles being disposed eccentric to each other, an adjustable eccentric and a means meshing with the last named pinion on the drive shaft for rotating said adjustable eccentric to oscillate the housing and carry the lens-carrying spindle across the grinding tool.

10. In a lens-grinding machine, the combination of a bed plate, a tubular standard vertically disposed thereon, a housing pivotally mounted on the standard, a vertically disposed drive shaft extending through said standard terminating in said housing, a pinion on the upper end of said drive shaft, an idler gear mounted on the housing meshing with said pinion, a lens-carrying spindle vertically mounted in the housing, a gear fixed on said spindle in constant mesh with said idler gear and rotatable thereby, means for reciprocating said spindle while being rotated and while the gear thereon is in mesh with the idler, a pinion on the drive shaft below the bed plate, an idler gear mounted on the bed plate in mesh therewith, a verti-

cally disposed spindle mounted in said bed plate, a gear on said spindle in constant mesh with said idler and rotated thereby to revolve the spindle, the gear on the lens-
5 carrying spindle being of smaller diameter than the gear on the last named spindle and said spindles being disposed eccentric to each other, an adjustable eccentric a means
10 meshing with the last named pinion on the drive shaft for rotating said adjustable eccentric to oscillate the housing and carry the lens-carrying spindle across the grind-

ing tool, a detachable and rockable lens-holder on said lens-carrying spindle, and means on said spindle to normally retain 15 said lens-holder in contact with the grinding tool.

In testimony whereof I have hereunto set my hand in the presence of two subscribing witnesses.

FRANK SCOVILLE.
